UNITED STATES PATENT OFFICE.

AARON H. WOLF, OF MYERSTOWN, PENNSYLVANIA.

WATCH-HOLDER FOR AUTOMOBILES.

1,216,531.

Specification of Letters Patent. Patented Feb. 20, 1917.

Application filed March 23, 1916. Serial No. 86,173.

To all whom it may concern:

Be it known that I, AARON H. WOLF, a citizen of the United States, residing at Myerstown, in the county of Lebanon, State of Pennsylvania, have invented certain new and useful Improvements in Watch-Holders for Automobiles; and I do hereby declare the following to be a full, clear, and exact description of the invention, such as will enable others skilled in the art to which it appertains to make and use the same.

The present invention is directed to improvements in watch holders particularly adapted to be attached to the steering post of an automobile, and has for its object to provide a device of this character which when in place will support a watch in a position to be conveniently observed by the driver.

20 A further object of the invention is to provide a holder of this character so constructed that the same can be used for supporting watches of different sizes.

With these and other objects in view, this invention resides in the novel features of construction, formation, combination and arrangement of parts to be hereinafter more fully described, claimed and illustrated in the accompanying drawing, in which:—

30 Figure 1 is a side elevation of the device showing the same attached to the steering post.

Fig. 2 is a sectional view on line 2—2 of Fig. 1.

35 Fig. 3 is a section view on line 3—3 of Fig. 1.

Fig. 4 is a sectional view on line 4—4 of Fig. 2.

The device consists of an arm 1 said arm 40 having one of its ends provided with a bar 2, while the other end thereof is provided with furcations 3 which are provided with slots 4, the purpose of which will appear later.

A pair of jaws 5 are provided, said jaws 45 being semi-circular in cross section and having their convexities confronting and provided with felt packing 6 so that when a watch is clamped between said jaws the watch will be protected from being 50 scratched. The extreme outer ends of jaws 5 are provided with confronting notches 7 which accommodate the stem of the watch.

The inner ends of the jaws 5 terminate in arms 8, said arms being pivotally mounted 55 in the slots 4, and have their inner ends provided with lugs 9 which are alined with the lugs 10 carried by the arm 1, said lugs serving to hold the coiled springs 11 in place.

The bar 2 is riveted to a strap 12 which is adapted to be engaged around the steering post of the machine so as to hold the device in a position so that the watch will be held in the line of vision of the driver.

What is claimed is:

A watch holder of the class described comprising an arm, means carried by the arm for detachably engaging a support, the forward end of said arm having furcations 70 carried thereby, said furcations being provided with slots, a pair of jaws adapted to clamp a watch, said jaws having their inner ends provided with arms, said arms being pivotally mounted in the slots, and springs 75 located on opposite sides of the first named arm and having their inner ends engaged therewith and their outer ends engaged with the inner ends of the second named arms.

In testimony whereof, I affix my signature, in the presence of two witnesses.

AARON H. WOLF.

Witnesses:

BRIGHT C. LINDENMUTH,
ALBERT NYE.
